ELMER G. MANSFIELD, OF BUFFALO, NEW YORK, ASSIGNOR TO BUFFALO SPECIALTY COMPANY, OF BUFFALO, NEW YORK, A CORPORATION OF NEW YORK.

FLOOR-POLISHER.

1,114,163.

Specification of Letters Patent.

Patented Oct. 20, 1914.

Application filed March 26, 1913. Serial No. 756,842.

To all whom it may concern:

Be it known that I, ELMER G. MANSFIELD, a citizen of the United States, residing at Buffalo, in the county of Erie and State of New York, have invented new and useful Improvements in Floor-Polishers, of which the following is a specification.

This invention relates to a polishing device designed more especially for applying a suitable cleansing and polishing material to hard-wood floors, wainscoting and other surfaces and for polishing the same.

One of the objects of my invention is the provision of a simple and inexpensive implement of this character by which the polish can be first applied to the floor or other surface and the latter then polished, the device having for this purpose two separate faces either of which can be readily presented to the surface to be treated.

A further object is to provide the device with an efficient polishing pad or covering which requires no separate means for fastening it to the head or body of the polisher.

Another object is to so combine the polishing head with its handle that notwithstanding the inclined position assumed by the handle in operating the device, the pressure is evenly distributed over the entire surface of the head, rendering all portions thereof equally effective and equalizing the wear on the polishing pad.

In the accompanying drawings: Figure 1 is a perspective view of the polisher with the covering in place. Fig. 2 is a similar view with the covering removed. Fig. 3 is a cross section of the device, taken through the handle pivot, the covering being omitted.

Similar figures of reference indicate corresponding parts in the several views.

The improved device comprises a polishing head 1, preferably consisting of an oblong board or block of oak or other suitable material, say about nine inches in length, six inches in width and three-fourths of an inch in thickness. It may, however, be made of any other desired dimensions. To avoid marring furniture, baseboards, &c., the board 1 may be provided around its edge with a buffer 2 of felt or other soft material.

Attached to the board 1 is a handle 3 of sufficient length to permit the operator to reciprocate the device without stooping. In

the preferred construction shown, the handle has a metallic shank 4 pivoted at its lower end in a longitudinal slot 5 of the board by a transverse pin 6. As shown in Fig. 3, this pin preferably extends across the full width of the board, in order to stiffen it and resist warping thereof. The slot 5 is arranged centrally in the board and extends to its rear edge, to permit the handle-shank to pass through it from either side of the board, in reversing the polisher, as hereinafter described.

A polishing pad or covering 7 of appropriate material is applied to both sides of the board 1, so that one side may be used for applying a liquid or other polish to a hard-wood floor or other surface to be treated, and the other side for rubbing or polishing the surface after the liquid has been applied. For this purpose, I prefer to employ a sack-like covering of knitted cotton or similar elastic or flexible material such as used for sweater-coats, which is snugly drawn over the board. This sack is closed on all sides, and its neck or open end 8, through which the handle 3 passes, is preferably of such a diameter relative to the normal inclined position and pivotal movement of the handle, that the neck is stretched or distended by the handle in moving the polisher back and forth over the floor or other surface. During every backward stroke of the polisher the angularity of the handle with reference to the board increases, with the result that the neck of the sack is stretched forwardly, thereby drawing the bottom portion of the sack up around the rear edge of the board and preventing it from becoming displaced or from creeping forward thereon during the backward stroke of the polisher. Obviously, rearward displacement of the sack on the board during the forward stroke of the polisher is prevented by the closed end of the sack. By this construction, an inexpensive, one-piece covering is produced which can be readily applied and removed and which requires no separate fastenings of any kind for securing it to the polishing head.

The handle may be reversibly pivoted to the head or board 1 at any suitable point between its ends, but it is preferably pivoted a short distance in rear of the transverse median line of the board, as shown in Fig. 2.

If the handle of the polisher, in its use, were normally held perpendicular to the board, the pressure would obviously be equalized over all portions of the board by pivoting the handle to the center thereof. But inasmuch as the handle is normally inclined at an angle of approximately forty-five degrees, it is found that with a centrally pivoted handle less pressure is exerted on the rear 5 than on the front portion of the polishing head, with the result that the covering becomes worn unevenly and only a portion of the polishing surface is effectively utilized. By pivoting the handle behind the center of 10 the board, as shown, the pressure of the handle, although exerted in a plane oblique to the board, is nevertheless equalized over its entire surface, thus obtaining the full efficiency of the polisher and causing the 15 covering to wear uniformly.

In the use of the device, after drawing the covering over the head, a suitable polish or cleanser, preferably in liquid form, is applied to one side of the head which latter 20 is then rubbed back and forth over the surface to be cleaned and polished. After the 25 polish has been thus applied, the head is reversed to present its other or polishing side to said surface, the handle-shank 4 swinging 30 through the slot 5 during this operation.

The head is then reciprocated over the surface as before, until properly polished.

I claim as my invention:

1. A polisher, comprising a head, a handle pivoted to said head to swing lengthwise 35 thereof, and a covering of flexible material inclosing said head and consisting of a sack having its neck arranged at the rear end of the head, the handle extending through said neck, whereby the handle by its pivotal 40 movement stretches the neck and prevents displacement of the sack on the head.

2. A polisher comprising a head having a suitable covering and a longitudinal slot extending to its rear end, a swinging handle 45 arranged in said slot, and a pivot-pin passing transversely through said head and the portion of the handle arranged in said slot.

3. A polisher comprising a flat-sided head having a longitudinal slot extending to its 50 rear edge, a handle reversibly pivoted in said slot, and a sack-like covering of flexible material inclosing said head and having a neck which receives said handle.

Witness my hand this 24th day of March, 55
1913.

ELMER G. MANSFIELD.
